UNITED STATES PATENT OFFICE.

HARRY C. CLIPPINGER, OF AKRON, OHIO, ASSIGNOR TO MARK E. METZGER
AND DANIEL W. BROWN, OF AKRON, OHIO.

ARTIFICIAL BAIT.

No. 831,831.

Specification of Letters Patent.

Patented Sept. 25, 1906.

Application filed February 4, 1905. Renewed July 9, 1906. Serial No. 325,315.

To all whom it may concern:

Be it known that I, HARRY C. CLIPPINGER, a citizen of the United States, residing at Akron, in the county of Summit and State of Ohio, have invented a new and useful Improvement in Artificial Bait, of which the following is a specification.

The invention relates to an artificial minnow used as a bait for catching fish by suspending it in a current of water or drawing it through the same on the end of a line; and the objects of the improvement are, first, to provide means for oscillating the tail or a fin laterally, so the minnow will meander or wiggle through the water in simulation of the movements of a natural minnow, and especially to apply the means in such a manner as will permit the use of reversely-rotating spinners at both ends of the minnow and will render unnecessary the use of weights or other special appliances for preventing a rotation of the body or a twisting of the draft-line, and, second, to provide an elastic support for the hooks on the sides of the minnow.

It has been customary to oscillate the tail of an artificial minnow by means of a rotatable axial shaft or rod actuated by a screw-wheel or spinner located at the forward end of the body, to the end of which rod the draft-line is usually attached by a swivel. The turning of such a rod in its bearings tends to rotate the body of the minnow, and the friction of the swivel tends to twist the draft-line, so that with a rotatable shaft it is practically necessary to provide special means for preventing the rotation or twisting of the body and the line. Furthermore, the hooks, which are usually attached on the sides of the minnow by a loop connection, are apt to become tangled with each other or otherwise caught in an improper position. These difficulties are overcome and the objects named above are attained by the construction, mechanism, and arrangement illustrated in the accompanying drawings, in which—

Figure 1 is a side elevation of the minnow, showing part of the rear end in section; Fig. 2, a plan view of the minnow, showing how the tail is oscillated; Fig. 3, a detached perspective view of the axial rod, showing the rear spinner thereon located slightly forward from its rear end bearing; Fig. 4, a detached

perspective view of the tail; and Fig. 5, a side elevation of the rear part of a minnow, showing the device adapted to oscillate a fin.

Similar numerals refer to similar parts throughout the drawings.

The rearward-projecting axial shaft or rod 1 is securely attached to the rear end of the body 2 of the minnow, and this rod may extend through the body and project forward from its front end, and the idle spinner 3 may be swiveled on such forward projection and the draft-line 4 attached thereto; but these features are not part of the present invention.

The rear or operating screw-wheel or spinner 5 is swiveled on the axial rod at the rear end of the body, preferably by means of the sleeve or hub 6. A suitable stop, as the annular flange 7, is provided on the rod to form a rear end bearing for the spinner, and a cam, preferably the eccentric ring 8, is formed or attached on the hub of the spinner. 75

The tail 9 is attached to the rod on the pivot 10, which is preferably perpendicular to the rod, and the lateral arms 11 are provided on the tail, which arms extend on each side of the eccentric ring adjacent to, or it may be abutting against, its opposite peripheral edges, so that when the ring is rotated by the turning of the spinner the tail is oscillated on its pivot.

If it is desired to adapt the device to the fin 12, as shown in Fig. 5, the eccentric ring 8^a is located on the forward end of the hub 6^a, and the fin is attached directly to the body on the pivot 10^a and is provided with the lateral arms 11^a, which are extended and curved to straddle the ring, so that the fin is operated in the same manner as described for the tail, and with this arrangement a set of hooks 13^a can be attached on the rear end of the rod. 85

The belly of the minnow is usually balanced or weighted so that it will normally stand right side up, and by arranging the two spinners to rotate in opposite directions, which is the practice when forward and rear spinners are used, the tendency of one spinner to turn the body from its normal position is overcome by the reverse tendency of the other. 95

The usual hooks 13 are attached on opposite sides of the minnow by the loop connections 105 14. The transverse apertures 15 are pro-

vided through the minnow-body a short distance back of the loops, and the elastic links 16 are located in the apertures and fastened to the shanks of the hooks on each side. Ordinary rubber bands may be used for these links, in which case the ends of the bands are merely looped over the shanks of the hooks. These elastic links permit a limited movement of the hooks, but hold them in proper position against the sides of the minnow as against any ordinary resistance.

What I claim as my invention, and desire to secure by Letters Patent, is—

1. An artificial minnow comprising a body, 15 an axial rod securely attached on the end thereof, a spinner with a cam swiveled on the

rod, and a tail pivoted on the rod and having lateral arms arranged to straddle the cam.

2. In an artificial minnow, a body, hooks connected by loops to opposite sides thereof, 20 there being a transverse aperture in the body back of the loops, and an elastic band in the aperture attached to the respective hook-shanks.

In testimony whereof I have signed my 25 name to this specification in the presence of two subscribing witnesses.

HARRY C. CLIPPINGER.
